FIG. 1

FIG. 2

INVENTOR

Howard L. Forman
BY
Philip G. Hilbert

ATTORNEY

UNITED STATES PATENT OFFICE

163,032

TRAY OR SIMILAR ARTICLE

Howard L. Forman, Belle Harbor, N. Y., assignor to Ben Forman & Sons, Inc., New York, N. Y., a corporation

Application February 3, 1951, Serial No. 14,095

Term of patent 14 years

(Cl. D44—10)

To all whom it may concern:

Be it known that I, Howard L. Forman, a citizen of the United States, residing at Belle Harbor, in the county of Queens and State of New York, having invented a new, original, and ornamental Design for Tray or Similar Article, of which the following is a specification, reference being had to the accompanying drawing, forming part thereof.

In the drawing

Fig. 1 is a top plan view of a tray or similar article, showing my new design.

Fig. 2 is a longitudinal sectional view taken on the line 2—2 of Figure 1.

I claim:

The ornamental design for a tray or similar article, as shown.

HOWARD L. FORMAN.
